G. G. MOSELEY & A. C. CAMERON.
TOOTH BRUSH HOLDER AND STERILIZER.
APPLICATION FILED JULY 2, 1912.

1,051,433.

Patented Jan. 28, 1913.

UNITED STATES PATENT OFFICE.

GAYLE G. MOSELEY AND ANDREW C. CAMERON, OF REDLANDS, CALIFORNIA.

TOOTH-BRUSH HOLDER AND STERILIZER.

1,051,433.

Specification of Letters Patent. Patented Jan. 28, 1913.

Application filed July 2, 1912. Serial No. 707,246.

To all whom it may concern:

Be it known that we, GAYLE G. MOSELEY and ANDREW C. CAMERON, residing at Redlands, in the county of San Bernardino and 5 State of California, have invented a new and Improved Tooth-Brush Holder and Sterilizer, of which the following is a specification.

This invention relates to cases or holders 10 for tooth brushes or the like, and it has for its object to provide a simple, inexpensive and neat appearing means for incasing a tooth or similar brush, which is practically dust proof and which is also designed for 15 holding a sterilizing medium in such manner that in the ordinary carrying or holding of the brush the latter will become thoroughly sterilized.

Our invention also has for its object to 20 provide a very simple and easily carried case for holding tooth brushes and having special provision for holding disinfecting or sterilizing tablets or like bodies that evaporate under air circulation, and in which the 25 several parts are so arranged that a continued circulation of sterilized air is maintained within the said case.

With other objects in view that will hereinafter appear our invention consists in a 30 brush holder and sterilizer embodying the peculiar and novel features of construction hereinafter fully described, specifically pointed out in the appended claims and illustrated in the accompanying drawings, 35 in which:

Figure 1, is a perspective view, partly in section, of our invention, the same being shown as in use. Fig. 2, is a vertical section, of the same on an enlarged scale. Fig. 40 3, is a detail view of the lower end of the holder, the removable bottom being shown. Fig. 4, is a perspective view partly in section of the perforated tablet holding box, the clip member and the washer and the 45 fastening eyelet hereinafter specifically referred to.

In carrying out our invention, we employ a container or holder 1, preferably of tubular shape and in practice made of different sizes to suit the different sizes of the brushes to be carried or contained therein.

The holder or container 1 may be of any desired material, sheet metal, polished or nickelated, glass or wood, but in every instance 50 with an open lower end which for a short

distance from the bottom is reduced in diameter to provide for receiving the removable bottom member 3 that is internally threaded as at 30 to screw onto the threaded face 10 of the reduced end of the holder 1, 55 the several parts being relatively so formed that when the member 3 is screwed home the outer face of the said member 3 and the outer face of the member 1, as also the inner faces of the members 1 and 3, will be flush 65 for permitting easy and thorough cleansing of the interior of the holder.

4 designates the top or cap member of the holder and it is hinged at one edge to the body of the holder 1, its lower edge and the 70 upper edge of the holder 1, being formed to provide for tight snap closure of the cap 4 when down. Cap 4 has one or more small openings 40 and the bottom member 3 has a central aperture 31, the said openings providing for ventilating the holder and permitting a continuous circulation therethrough.

9 designates a perforated box adapted for being held in the desired position by the 80 clip 5 and for holding a compressed sterilizing medium, preferably a tablet of trioxymethylene, since the said substance readily gives off formaldehyde gas at ordinary temperature, it being understood a 85 continuous generation and circulation of the disinfectant is maintained so long as any particle of the tablet or substance 7 remains unevaporated, and by reason thereof a constant mixture of formaldehyde gas 90 and air surrounds the tooth brush within the container. The aperture 31 also serves as a means, in connection with an eyelet, for securing in place a spring clip device, the base 50 having a central opening for the 95 passage of the air and the eyelet 8 that secures the clip, a metal washer 61, and the bottom member 3 together, see Fig. 2.

From the foregoing taken in connection with the drawings, the complete arrangement, and the advantages of our invention will be readily apparent.

By reason of constructing the parts as shown and described they can be very economically and easily manufactured and 105 easily cleaned.

By providing the bottom with a central aperture for the passage of air, and a tablet cup formed as stated, a simple eyelet fastener with an intervening washer is all 110

that is necessary to secure the tablet box in place and so positioned that a thorough mixing of the incoming air passing through the perforations in the cup is maintained. 5 Furthermore a positive holding of the tablet cup is provided and the placing of a new tablet into the cup made easy by simply unscrewing the bottom 3 and opening the box 8. To securely hold the tablet box in place, 10 during ordinary handling of the holder the clip 50 has spring fingers 52 that snap over and clamp the tablet box, as shown.

What we claim is:

1. A holder comprising a body having a 15 top and a bottom, a sterilizing element holder and a hollow rivet securing the said holder in the said bottom and forming an

air passage through the said bottom, and holder.

2. As a new article, a holder for tooth 20 brushes and the like comprising a body, a top, a removable bottom, a sterilizing element holder, said holder being a spring clip, a perforated box for holding the sterilizing element removably mountable upon 25 the clip and an eyelet that secures the clip upon the bottom, said eyelet extending through the bottom and forming an air passage.
